UNITED STATES PATENT OFFICE.

JOÃO P. SIMMONS AND MANUEL C. PACHECO, OF NEW BEDFORD, MASSACHUSETTS.

BUILDING-BLOCK CONSTRUCTION.

Application filed February 9, 1924. Serial No. 691,659.

To all whom it may concern:

Be it known that JOÃO P. SIMMONS and MANUEL C. PACHECO, citizens of the United States, residing at New Bedford, in the 5 county of New Bedford and State of Massachusetts, have invented certain new and useful Improvements in Building-Block Constructions, of which the following is a specification.

10 The invention has for an object to effect an improvement in building blocks and particularly those adapted to be cast in concrete and now so generally used for the erection of masonry walls. A particular aim of the 15 invention is to provide a block which will be especially proof against dampness by reason of its structural form, when incorporated in a wall. A further aim is to give a novel construction in which heat insulation will 20 be effected. It is also an aim to insure the wall against dampness at the inner face by provision of air spaces by which the capillary transmission of moisture will be minimized, as well as ventilation effected by which 25 the dampness or water may be evaporated, if necessary, as might be found advisable where a retaining wall is erected in a damp situation. It is a further important aim to 30 so construct the block that in the application of mortar upon courses thereof, an interlocking, keying or linking effect will be developed between the ends of mutually adjacent blocks.

It is an important purpose of the invention 35 to give a block which will have the advantage of one having horizontal upper and lower faces, with regard to stability during erection of a wall and thereafter, and which will also have the effect of shedding 40 or preventing ingress of water at the horizontal joints.

Additional objects, advantages and features of invention reside in the structural relation of the elements of the block, and 45 the co-action of such blocks when utilized in a wall, as will be readily understood from the following description and accompanying drawing, in which,

Figure 1 is a fragmentary elevational view 50 of a wall constructed in accordance with our invention, with parts broken away to show sections of the blocks, on the lines *a* and *b*, respectively, of Figure 2, as indicated at *a* and *b* in the elevation.

Figure 2 is a cross section of a wall con-

structed with our block on the line 2—2 of Figure 3.

Figure 3 is a top view of one of the blocks,

Figure 4 is an end elevation thereof,

Figure 5 is a perspective view of one of 60 the blocks,

Figure 6 is a possible modification of the form of the top and bottom of the block, as viewed in Figure 4.

Figure 7 is a similar view of a further 65 modification showing also the mortar joint between two superposed blocks.

Figure 8 is an end view of a block showing a still further modification in cross sectional form.

There is illustrated a block 10, preferably 70 in the form of an oblong rectangle as viewed in plan, and in the particular instance illustrated being twice as long as it is wide. The block includes a right side or front face 11, and a back or inner face 12. The top of the block is formed with a rear flat part 13, while the front part of the top is offset therebelow, forming a vertical rectilinear shoulder 14 extending longitudinally of the block 75 so a little to the rear of the medial line thereon, the front top portion 15 being sloped from the shoulder 14 to the front face 11. The bottom of the block is correspondingly formed so that it may set snugly upon the 80 top of a similar block, excepting that the horizontal rear part 16 is slightly wider from front to rear than the sloping part of the bottom of the block, indicated at 17, the shoulder 18 therebetween corresponding to 85 90 the shoulder 14 being located a little to the front of a medial line on the bottom of the block. This allows a space between the shoulders of superposed blocks, to accommodate mortar, as will be readily understood. 95

The ends of the blocks are vertical, so that when the blocks are viewed from front or rear they present a rectangular form. In the rear part of the block and opening on the flats at top and bottom there are vertical 100 105 bores or passages 19 equally spaced longitudinally in a series parallel to the back face 22, while in the ends of the block, aligned with these passages there are formed semi-cylindrical recesses 20 in a relation to form a continuation of the series when similar blocks abut. Arranged in staggered relation with the passages 19, similar passages 21 are formed in the front portion of the block, in a series parallel to the front face 11, and 110

from the end passages 21 in the block, slots 22 open on the end faces of the block extending the full height of the block.

In the use of this form of block usual masonry methods are followed in the main. Two methods may be followed as to breaking joints in the laying of courses, one of which is illustrated in Figure 1, which consists of laying a course of the blocks so that 10 the end of one will fall adjacent the center of one of the passages 19 in the rear part of the lower course, as dotted at the left of the center in Figure 3. If desired, however, the joints of one course may align with the 15 middle of the block in adjacent courses, in which event the body portion of the block between the passages will align with the passages of superposed blocks. In the laying of mortar, as is well understood, the 20 "keying" effect produced when a block is set in the mortar will result in the key portion extending through the slot 22 and integrally within the respective passages 21 thereadjacent, so that the blocks in a course 25 are held together longitudinally somewhat better than would be the case in blocks which have merely plain surfaces abutting at the ends.

By the method illustrated in Figures 1 30 and 2, the wall permits the running of water pipes or steam pipes vertically in the wall when desired.

As is well understood in the art of building masonry walls, occasional openings are 35 left in joints by reason of insufficient mortar; and by reason of the inclination of the outer part of the blocks, as at 15 and 17, gravity will prevent seepage of water 40 through such interstices in walls constructed with my block.

The shoulder 14 is also instrumental in preventing entrance of water to a large extent by acting as a dam confining to the outer parts of the wall any excessive amount 45 of water which may gain access thereto, as might occur through a vertical joint, and also serves as a material aid in strengthening the wall against collapse from lateral pressure.

50 It may be found desirable to utilize the shoulder 14 without the inclined upper and lower surfaces on the block outwardly thereof, and making both parts of the top and bottom horizontal, as indicated in Figure 6. 55 Also, as shown in Figure 7, it may be found desirable to form the shoulder 14 exactly on the medial line of the block, so that in placing one upon another in a wall, the lower

shoulder 18^a will engage directly against the shoulder 14^a, and thus aid in alining the 60 courses and making better accuracy in fitting, without excessive expenditure of time.

In Figure 8 there is illustrated a further form of block in which the top and bottom surfaces are modified to the extent that the 65 front and inner portion of each is in the same plane, and a medial longitudinal rib 50 semi-circular in cross section is formed on the top of the block, while a correspondingly located groove 51 is provided in the 70 bottom of the block. The groove is of similar form, but is preferably of slightly larger size, so as to readily accommodate a certain amount of mortar over the rib in the joint 75 between two superposed blocks.

It is an advantage of our invention also that while affording the usual advantages of a cored block in heat insulation and dryness, and while permitting the provision of the water-blocking element 14, the block also 80 has great load sustaining strength, and will be found to obviate the need for filling cored openings with concrete as has been done with many forms of concrete blocks at present in some situations. The central uncored part is of great strength in itself. This will improve the performance of the block in resisting fire damage. The shoulder 14 with the inner top surface continued therefrom is not very liable to breakage and 85 in the event that a considerable part should be broken away, the water blocking effect will not be destroyed owing to the continuation of the remainder of the top at the same elevation.

90 What is claimed:—

A building block comprising inner and outer integral sections each having a longitudinally arranged series of vertical passages therethrough in equal spaced relation, the passages of one section being in staggered relation to those in the other, slots of less diameter than the passages and opening on the top and bottom of the blocks being formed at each end of the block forming 100 communication between respective passages and the ends of the block, and being of a width to permit the formation of a substantial key to oppose longitudinal separation of the blocks by the extrusion of mortar 105 from joints on which the slots and passages abut when such blocks are laid as described.

110 In testimony whereof we affix our signatures.

JOÃO P. SIMMONS.
MANUEL C. PACHECO.
